UNITED STATES PATENT OFFICE.

HENRY AIKEN, OF PITTSBURG, PENNSYLVANIA.

TONGS-OPERATING MECHANISM.

SPECIFICATION forming part of Letters Patent No. 729,251, dated May 26, 1903.

Application filed December 8, 1902. Serial No. 134,240. (No model.)

To all whom it may concern:

Be it known that I, HENRY AIKEN, of Pittsburgh, Allegheny county, Pennsylvania, have invented a new and useful Tongs-Operating Mechanism, of which the following is a full, clear, and exact description, reference being had to the accompanying drawings, forming part of this specification, in which—

Figure 1 is a sectional side elevation of 10 tongs provided with my improved operating mechanism. Fig. 2 is a front elevation, on a larger scale, showing the trolley of a charging-crane provided with my mechanism. Fig. 3 is a top plan view of the trolley. Fig. 4 is 15 a cross-section on the line IV IV of Fig. 1, the parts being shown on a larger scale. Fig. 5 is a broken side elevation showing the driving connections and the lower bearings. Figs. 6 and 7 are sectional side elevations 20 showing the tongs and the movable head carrying the mechanism for operating them; and Fig. 8 is a cross-sectional view of a friction-clutch, which I preferably employ.

My invention relates to the tongs employed 25 in steel-mills, and is designed to provide simple and efficient mechanism for raising and lowering and turning them, especially such as are used for handling ingots in vertical soaking-pits, which are known as "drawing" 30 and "charging" pit cranes.

In the drawings I show a trolley 2, having 35 wheels 3, movable upon tracks 4, carried on crane-girders 5, these girders forming part of an ordinary overhead traveling crane. The longitudinal travel of the overhead crane and the transverse travel of the trolley bring the tongs to any desired point in the space covered in the usual manner. Depending from the trolley is a stiff vertical guide-frame 6, 40 which is rigidly attached to the trolley-frame and contains upper and lower bearings 7 and 8 for a pair of vertical squared shafts 9 and 10. A movable frame or head 11 is arranged to be moved vertically within the guide-frame, this head being supported and raised 45 and lowered by means of chains 12 12, secured to hooks 13 on the frame and extending over a hoisting-drum 14 on the trolley, to which they are secured in the usual manner. The tongs, their vertical supporting-bar, and the operating mechanism are partially 50 counterbalanced by means of a weight, hung

on a wire rope 15, secured to the hoisting-drum. This drum is connected, by suitable gear-wheel 16, pinion 17, shaft 18, gear-wheel 19, having friction-clutch connection with shaft 18, pinion 20, shaft 21, toothed wheel 22, and pinion 23, with an electric motor 24 and brake 25, operated by solenoid 26. The motor 24 acts to raise and lower the tongs 55 mechanism vertically within the guide-frame and gives this movement with considerable rapidity. The operator is therefore liable to injure the moving parts by raising or lowering the tongs beyond the extreme point of its 60 movement, and to prevent injury from such cause I employ the friction-clutch connection at some point in the train of driving connections, so that in case either of overload or of the operator failing to stop the tongs at the 65 proper limit of stroke either top or bottom this friction-clutch connection will slip and allow the driving connection to rotate without moving the tongs mechanism. I preferably attain this result by means of a disk or 70 wheel which is frictionally held by means of springs between the friction-faces of two disks or wheels on opposite sides thereof. By adjusting the spring-tension the point at 75 which the slip will occur may be regulated to 80 get the desired result.

The head or vertically-movable frame 11 is circular in form, containing a central squared shaft 27, passing through a square hole in the hub 28 of a gear-wheel 29. The hub 28 rests 85 within a bearing in the lower head 30 of the frame, and loosely surrounding the upper part of the hub is a duplex cam-wheel 31, formed integrally with a gear-wheel 32. Between the cam-wheel 30 and the wheel 29 is 90 placed an annular friction-disk 33, upon which the cam-wheel rests, an oiler 34 being preferably provided to lubricate the bearing-surfaces. To the upper end of the squared shaft 27 is secured a cross-head 35, with recessed ends fitting within vertically-extending guides 36, secured within opposite sides of the frame 11. Within the opposite ends of this cross-head are pivoted transverse rollers 37, which rest upon the cam-wheel 95 100 which acts to raise and lower the shaft 27, and thereby open or close the tongs. To rotate the cam-wheel and open or close the tongs, I provide a pinion 38, which is car-

ried upon the squared shaft 10, and to turn the tongs I provide a pinion 39 upon the squared shaft 9, which pinion engages the teeth of the wheel 29. The shaft 10 is connected at its upper end by bevel-gearing 40 with a horizontal shaft 41 on the trolley, which is connected by slow-motion gearing 42 with an electric motor 43. The shaft 9 is similarly driven through bevel-gear 44 and slow-motion gearing 45 from motor 46. The motors 43 and 46 are provided with brakes 47, controlled by solenoids 48.

The shaft 27 extends downwardly through a tubular support 49, secured to the lower head 30 of the frame 11, and on the lower end of this support is supported a frame 50, containing on opposite sides the bearings 51 for the tong-levers 52. These levers cross each other in the form shown, their crossing-arms 53 being connected by links 54 with a cross-head 55, loosely surrounding the lower end of the tubular shaft 49 and carried on collar 49' rigid with the tube. It is evident that with this arrangement the raising and lowering of the shaft 27 will open or close the tongs. The tongs are raised and lowered by raising and lowering the frame 11 through the chains leading over the hoisting-drum, and the tongs are turned or rotated by actuating the squared shaft 10, which acts upon the wheel 29, having a square hole in its hub through which the squared shaft 27 extends.

The advantages of my invention result from the simplicity and effectiveness of the apparatus. The hoisting-drum provides a rapidly-operating means for raising and lowering the tongs, while means are provided for turning and for opening and closing the tongs, which means can be easily operated from the trolley. The movements are positive and under control, while injury from excess vertical movement is avoided.

Many variations may be made in the form and arrangement of the parts without departing from my invention.

I claim—

1. In tongs-operating mechanism, a movable trolley having a hoisting-drum, gripping mechanism supported on a flexible connection leading to the winding-drum, mechanism for turning the gripping mechanism relatively to the trolley, and a rotary element connected to the tongs and arranged to open and close them by its rotation; substantially as described.

2. In tongs-operating mechanism, a movable trolley having a hoisting-drum, a vertically-movable frame supported from said drum and having a depending member carrying the tongs, mechanism on the trolley for turning the tongs, and a rotary element connected to the tongs and arranged to open and close them by its rotation; substantially as described.

3. In tongs-operating mechanism, a movable trolley having a hoisting-drum, a grip-

ping mechanism supported on a flexible connection leading to the winding-drum, a vertical shaft on the trolley arranged to turn the tongs at any level to which they are moved, and a rotary element arranged to open and close the tongs by its rotation; substantially as described.

4. In tongs-operating mechanism, a movable trolley having a hoisting-drum, a vertically-movable frame supported from said drum and having a depending member carrying the tongs, and shafts having connections arranged to rotate to open and close the tongs respectively, and a rotary element arranged to actuate the tongs-actuating shaft by its rotation; substantially as described.

5. In tongs-operating mechanism, a trolley, a hoisting-drum thereon arranged to support and raise and lower a vertically-movable frame, tongs supported by said frame, and a rotary element on the frame arranged to open and close the tongs by its rotation; substantially as described.

6. In tongs-operating apparatus, a trolley having a hoisting-drum and a depending guide-frame, a vertically-movable supporting-frame carried by the drum and guided by the depending frame, said frame having a depending member carrying the tongs, a rotary element on the carrying-frame arranged to open and close the tongs by its rotation, and another rotary element on said frame arranged to turn the tongs; substantially as described.

7. In tongs-operating apparatus, a trolley having a hoisting-drum, a depending guide-frame supported on the trolley, a vertically-movable carrying-frame guided by the guide-frame and having flexible connections leading to the drum on the trolley, depending tongs supported by the carrying-frame, a rotary element on said frame arranged to open and close the tongs by its rotation, and another rotary element on said frame arranged to rotate the tongs; substantially as described.

8. In tongs-operating apparatus, a hoisting-drum, a vertically-movable frame supported and raised and lowered thereby, depending tongs supported by said frame, a vertically-movable rod or shaft arranged to actuate the tongs, and a rotary cam device on the frame arranged to raise and lower said actuating-shaft; substantially as described.

9. In tongs-operating apparatus, a trolley having a hoisting-drum, a depending guide-frame supported therefrom, a vertically-movable carrying-frame guided thereby, depending tongs supported upon said carrying-frame, a vertically-movable operating-bar arranged to open and close the tongs, a rotary cam device on the carrying-frame arranged to raise and lower the bar, and mechanism on the carrying-frame arranged to rotate the bar to turn the tongs; substantially as described.

10. In tongs-operating apparatus, a trolley having a hoisting-drum, a depending carrying-frame supported by a flexible connection

from the drum, a depending guide-frame carried by the trolley and arranged to guide the carrying-frame, depending tongs supported upon the carrying-frame, a rotary cam device on the carrying-frame having connections arranged to open and close the tongs, and a toothed wheel in the carrying-frame sliding over an actuating-shaft mounted in fixed bearings in the guide-frame; substantially as described.

11. In tongs-operating apparatus, a trolley, a hoisting-drum thereon, a vertically-movable frame supported by a flexible connection to the drum, tongs supported by said frame, mechanism on the frame for opening and closing said tongs, a rotary element arranged to open and close the tongs by its rotation, and a depending guide-frame for said carrying-frame; substantially as described.

12. In tongs-operating apparatus, a vertically-movable carrying-frame, tongs supported thereby, mechanism on said frame for opening and closing the tongs, flexible connections leading from the frame to a hoisting-drum, and an actuating-motor having a slip-motion connection with the drum; substantially as described.

13. In tongs-operating apparatus, a trolley having a depending guide-frame, a vertically-movable frame or head guided thereby and having flexible connections leading to a hoisting-drum on the trolley, depending tongs supported from said carrying-frame, a rotary cam device on said carrying-frame having connections arranged to open and close the tongs, and mechanism on the trolley for ac-

tuating the cam device; substantially as described.

14. A trolley having a hoisting-drum, a depending guide-frame supported thereon, vertically-extending angular shafts supported on said frame, a vertically-movable carrying-frame guided within the guide-frame and having tongs supported therefrom, a vertically-movable actuating-bar for the tongs, a rotary cam in the carrying-frame arranged to raise and lower said bar, a wheel in the carrying-frame arranged to turn the bar, and wheels arranged to move over the vertical shafts of the guide-frame and actuate the cam and the turning-wheel respectively; substantially as described.

15. In tongs-operating mechanism a hollow vertical post carrying the tongs, a rod or bar extending within the post and vertically movable to open and close the tongs, and cam mechanism for raising and lowering the rod or bar; substantially as described.

16. In tongs-operating mechanism a hollow vertical post carrying the tongs, a rod or bar extending within the post and vertically movable to open and close the tongs, cam mechanism for raising and lowering the rod or bar, and mechanism for turning said central bar to turn the tongs; substantially as described.

In testimony whereof I have hereunto set my hand.

HENRY AIKEN.
